UNITED STATES PATENT OFFICE

FREDERICK LACKNER, OF PITTSBURGH, PENNSYLVANIA, ASSIGNOR TO NEELY NUT AND BOLT COMPANY, A CORPORATION OF PENNSYLVANIA

METHOD OF MANUFACTURING NUTS

Application filed July 31, 1929. Serial No. 382,353.

This invention relates to a method of manufacturing nuts, and consists in improvements in the methods which are indicated in my Patents No. 911,599, dated February 9, 1909, and No. 1,039,145, dated September 24, 1912.

In forming nuts from flat stock, as disclosed in the patents above noted it has been found difficult to prevent fins from forming on the nuts at the edges where they are sheared from each other. The object of my invention is to provide a method of manufacturing nuts which are free from objectionable fins.

In the accompanying drawings, I illustrate a nut-forming machine which is advantageous in conducting my method. Figure I is a front elevation of the shaping jaws and adjacent parts of the nut-machine; Figure II is a sectional view taken on the plane II-II of Figure I, showing in addition, however, the front end of the punching head of the machine; Figure III is a front elevation of the punching head showing the relative positions of the two punches and the shearing die; Figures IV to XIII inclusive show the stock in the various positions, following the several steps from the start to the complete formation of a nut; Figure XIV is a sectional view taken on the plane XIV-XIV of Figure VI; Figure XV is a sectional view taken on the plane XV-XV of Figure IX; and Figure XVI is a sectional view taken on the plane XVI-XVI of Figure XIII showing the shearing matrix and the shearing die associated with the stock.

Except as hereinafter specified the nut-forming machine is constructed and operated as shown and described in my patents, above noted. The machine includes means operable to reciprocate the punch or die head 1, and the jaws 2 and 3 which are secured to the vertically operating slides 4 and 5 are organized with the mechanism of the nut-machine to be intermittently opened and closed. By following the several steps in the formation of a nut, my method will be understood.

Initially the strip of stock A is fed into the machine to lie between the jaws 2 and 3 and against the back wall or die 13. This posi-

tion is outlined in Figure IV, where it will be noted that the jaw 2 is formed with the faces a, b, c, d, e, and f, and that the jaw 3 has the corresponding faces a', b', c', d', e', and f' opposed thereto. The nut-machine is caused to move the jaws together—into the position shown in Figure V. A nut-blank B has received its first forming-contact with the machine; that is, the surfaces a, b and a', b' of the jaws 2 and 3 have pressed into the bar of stock A, and have partially separated and formed the nut-blank B therefrom. The surfaces b, c and b', c' form, in this position, the first nut-forming matrix. If the vertical width of the stock A is less than the distance across the opposite corners of a hexagonal nut (this equals the distance between the points o and p in Fig. V), the metal of the stock may be expanded by a punching die to completely fill the forming matrix. This will save metal, inasmuch as the metal which is often punched-out to form the hole of the nut, is in my practice expanded or displaced to complete the formation of the nut. For the reason that the stock is of less width than the nut, as pointed out, it is obvious that in the first matrix b, c, b', c' the metal will not form a sharp cornered blank adjacent the points o and p.

While the jaws 2 and 3 temporarily remain in the position illustrated in Figure V, the die head 1 is moved into the position shown in Figure II. Mounted to project from the face of the head are the two circular punching dies 6 and 7, and the shearing die 8. It will be noted that the die 6 is of less length than the die 7; that is, it projects a lesser distance from the face of the die head than the die 7. As the die head moves into closed position with respect to the jaws 2 and 3, the punch 6 enters the blank B and presses it to the form shown in Figures VI and XIV.

Next, the jaws are caused to open, and the stock is moved transversely thereof into the position shown in Figure VII. The jaws are closed again, and, as the jaws close, as indicated in Figure VIII, the blank B is seated in the second matrix, which is formed by the surfaces d, e and d', e'; the surfaces a, b, c

and a' , b' , c' cooperating simultaneously to start the formation of another nut blank C . Again, with movement synchronized relatively to the operation of the jaws 2 and 3, the head 1 is closed upon the stock, and the punch 7 presses further into the blank B , leaving only a central web B' (shown in Fig. XV) to be removed to complete the central hole of the nut. This second punching operation upon the blank B in the second matrix d , e , d' , e' has been found to render a more sharply or cleanly formed hexagonal nut. The die 6, in this movement, forms the initial indentation and expansion of the blank C .

It will be noted that the surfaces, such as the surfaces c and d , and c' and d' , of the jaws 2 and 3 do not diverge toward the stock to form a line, but in reality terminate in the narrow flat surfaces 9, which impress similar surfaces 10 on the stock between the successive nut blanks, and in effect space the adjacent nut blanks a slight distance from each other. Arranged in the die head are two blade members 20, which, during the punching operation, partially sever the nut blanks. Figure XV shows how the blank B is partially severed at 21 from the blank C . The advantage of this partial severing will presently be described.

After the blank B has been punched by the die 7, the jaws are opened and the stock is fed to the position indicated in Figure X. Figure XI shows the dies closed after the third movement of the head has been effected, this latter die movement resulting in the initial formation and punching of the nut blank D . Again the jaws are opened and the stock moves into the position shown in Figure XII, and subsequent operation of the machine starts the formation of nut E . When the punch or die head 1 is closed upon the stock in this latter position (shown in Fig. XIII) the first blank B is positioned without the jaws 2 and 3 and lies in front of the finishing and shearing matrix 30 which is formed in the die back 13. Movement of the head 1 brings the shearing die 8 against the blank B , and cooperating with the matrix 30 completely severs this blank from the adjacent blank C .

It is during this shearing operation that the objectionable fins, referred to above, were hitherto formed. Due to the previous operation of the blades 20, the fins, if formed at all, are formed on the side of nut adjacent the bottom of the slot 21. The nut, however, is forced into the finishing matrix 30 after it is sheared, and it is forced against the stop 32, whereupon, the finishing punch 33 is moved to complete the central opening of the nut, by removing the web B' . When the nut blank is positioned within this last matrix, which is formed in section to correspond to the finished nut, a substantial pressure may

be applied by the die 8 to press and expand the nut against the walls of the matrix, and thereby imbed the fins in the outer surfaces of the nut. It may be remarked that it is advantageous although not necessary to provide upon the face of the block 13 a V-shaped ridge 5 opposite to each blade 20 (Figs. II and XVI). Such a ridge will effect the formation of slight indentations upon the back of the stock A and in alignment with the grooves 20, whereby the shearing of the connecting web between the successive nut blanks will be readily started upon a medial line of the web.

Upon withdrawal of the head 1 and die 8, the stop 32 is moved to eject the nut blank, which is now ready to be tapped or internally threaded. The operation is continued to form successively other nut blanks from the stock.

What I claim is:

1. The method of manufacturing nuts which comprises the steps of progressively forging a strip of metal into a series of interconnected blanks, and progressively effecting the partial separation of each blank from the other in such manner as to leave a connecting web extending part way of the thickness of the metal between successive blanks, and subsequently causing the shearing of each of such connecting webs, in which shearing operation the web portions remaining upon the nut blanks are forged into coincident planes with the faces of said blanks.

2. The method of manufacturing nuts which comprises the steps of progressively shaping a strip of metal into a series of interconnected blanks, effecting the partial separation of each blank from the other in such manner as to leave a connecting web extending part way of the thickness of the metal between successive blanks, detaching such blanks from each other by causing a separation along said connecting webs, and forcing the remaining web portions into the faces of said blanks, as described.

3. The method of manufacturing nuts which comprises the steps of shaping a strip of metal into a series of interconnected blanks, effecting a partial separation of each blank from the other in such manner as to leave a connecting web of metal between successive blanks, detaching such blanks from each other by causing a separation along said connecting webs, and forcing the remaining web portions into the faces of said blanks, as described.

4. The method of manufacturing nuts which comprises the steps of shaping a strip of metal into a series of interconnected blanks, effecting the partial separation of each blank from the other in such manner as to leave a connecting web of metal between successive blanks, displacing the metal to form a hole part way through each blank, de-

taching such blanks from each other by causing a separation along said connecting webs, and completing the hole through each blank while forcing the web portions remaining on the detached blank into the faces thereof, as described.

In testimony whereof I have hereunto set my hand.

FREDERICK LACKNER.
